UNITED STATES PATENT OFFICE

150,182

DESIGN FOR A SWEATER

Berté A. Wiechmann and Fay W. Robson, Portland, Oreg., assignors to Jantzen Knitting Mills, a corporation of Oregon

Application March 7, 1947, Serial No. 137,450

Term of patent 3½ years

(Cl. D3—4)

To all whom it may concern:

Be it known that we, Berté A. Wiechmann and Fay W. Robson, citizens of the United States, residing at Portland, in the county of Multnomah, State of Oregon, have invented a new, original, and ornamental Design for a Sweater, of which the following is a specification, reference being had to the accompanying drawing, forming a part thereof.

In the drawing, the single figure is a view of the front side of a sweater showing our new design, the design on the rear side of the sweater being the same as on the front.

We claim:

The ornamental design for a sweater, substantially as shown and described.

BERTÉ A. WIECHMANN.
FAY W. ROBSON.
